of Delaware

Application June 10, 1942, Serial No. 446,475

4 Claims. (Cl. 179—171.5)

This application concerns a new and improved method of and means for phase modulating a carrier wave a controllable amount in accordance with signalling potentials of any type.

Use of my new and improved system has numerous advantages some of which will appear from the description thereof which follows:

In describing my system reference will be made to attached drawings wherein Figure 1 illustrates by block diagram a phase modulator arranged in accordance with my invention. Figure 2 illustrates more in detail the improved modulation circuits of a phase modulation system arranged in accordance with my invention; while Figure 3 is a vector diagram used to illustrate the manner in which phase modulation of a controllable amount is obtained by the use of my system.

Referring now to Figure 1 of the drawings, a crystal oscillator O is shown as supplying carrier waves to two phase modulators, PM and PM₁. The phase modulators are also supplied with modulating potentials from a source MP coupled by the lines to the two phase modulators. Note that the couplings between the source MP and the two phase modulators are reversed thereby indicating that in the separate phase modulators the carriers of common frequency are modulated in phase in opposed sense.

The phase modulated output is supplied to a converter C by way of two multipliers M and M₁, wherein the phase modulated carriers are multiplied to increase the phase displacement. This multiplication increases the frequency of the energy and the deviation thereof proportionally so that the degree of modulation is not changed. The multipliers M and M₁ have different multiplication factors, the factors differing by the integral 1. The converter C is of the mixing tube type and in the output thereof the summation of the phase deviations appears on the selected carrier. In the system illustrated the phase deviations accomplished in the modulation PM is in one direction and this phase deviation is doubled. In the phase modulator PM₁ the phase deviation is in the opposite direction and this deviation is tripled in multiplier M₁. At the output of converter C, the deviation of which is five times the deviation accomplished in one of the modulators, the difference frequency is selected and this new carrier is of the frequency of the crystal oscillator O and, consequently, is of substantially constant mean frequency. The selected carrier is again multiplied in frequency to the desired extent in the multiplier M₂ and multiplied and amplified in the unit MA before radiation.

In Figure 3 the vector A represents the carrier frequency supplied to both modulators PM and PM₁ and the vectors A₁ and A₂ represent a maximum phase deviation in opposite directions of the carrier under control in opposite directions of the modulating potentials in modulators PM and PM₁.

The output of the crystal oscillator O, which is used as a frequency control of the carrier frequency, is fed to two branches PM and PM₁ which are identical phase modulators. The audio modulation from MP is fed to these modulators in opposite sense so that the phase modulation is in the opposite sense. When the phase of one of the carriers in one phase modulator is advancing, the phase of the other carrier in the other phase modulator is retarding as indicated in Figure 3. The output of these modulators are fed respectively to, for example, a doubler and a tripler. The doubled and tripled wave energy whereon the phase deviation (not per cent deviation) has also been doubled and tripled is fed to a converter and the difference frequency selected at the output, this difference frequency being equal to the crystal oscillator frequency with five times as much phase modulation as was impressed on the carrier in the modulators. Further multiplication raises the phase deviation.

In Figure 2 I have shown a specific embodiment of my invention. In this figure the tube 10 is a crystal controlled oscillator of the electron coupled type comprising a grid 14 and a grid 12 coupled with a crystal 16, biasing resistance 18, charging resistance 20, and bypass condensers 22 and 23 for the production of oscillations of substantially constant frequency. The generated oscillations are supplied by electron coupling in the tube to the anode 24 and thence to a tuned circuit 26—28. This circuit may be tuned to the crystal frequency or a harmonic thereof. The oscillations from 26—28 are supplied to two identical balanced phase modulators. In the drawings similar parts in the two identical phase modulators bear similar reference numerals and only one thereof will be described.

The wave energy from 26—28 is supplied by a coupling condenser 27 to the grid 31 of an electron discharge device 33, amplified therein and fed by the anode 35 thereof to a tuned circuit 50 including an inductance 37 and a variable condenser 39. The terminals of the tuned circuit are connected to the anodes 44 and 46 of reactance tube modulators 40 and 42. One end of the tuned circuit 37—39 is also coupled by phase shifting circuits C, L and R, and C₁—L₁ and R₁

to the grids 54 and 56 of tubes 42 and 48 respectively. The cathodes of said tubes are connected to ground by resistances 52 and 48 shunted by bypassing condensers BP, thereby coupling or placing the impedances of the two tubes in shunt to a part at least of the tuned circuit 37-39, a point on which is coupled to ground by a large condenser 30. The grids 54 and 56 are also coupled by chokes RFC in push-pull relation to a secondary winding of a modulation transformer 51 coupled to a source of modulating potentials.

The phase shifters C, L and R and C₁-L₁ and R₁ are for the purpose of setting up on the anodes and control grids of the tubes 42 and 48 voltages displaced substantially 90° in order to obtain in a well-known manner reactive effects of unlike sign of the tubes in the balanced modulator. In the arrangements shown, the anodes 44 and 46 are connected to the opposite ends of inductance 37 so that the excitation on the said anodes are in phase opposition. The phase of the excitation on the grids 54 and 56 is also displaced about 90° by the phase shifters C, L and R and C₁-L₁ and R₁ with respect to the voltage on the anode 44. Since the voltage on the anode 46 is displaced about 180° with respect to the voltage on the anode 44, the voltage on the grids 54 and 56 is also displaced about 90° with respect to the voltage on the anode 46. In one of the tubes the grid voltage leads the plate voltage by about 90° and in the other tube the grid voltage lags the plate voltage by about 90°. As the reactances of the tubes are varied by the control potentials differentially one tube will increase inductive reactance, while the other tube will decrease capacitive reactance and vice versa. In this manner the differential modulation results in modulating the phase of the current supplied to the circuit 37-39. Moreover, during this modulation process any amplitude modulation produced in one of the tubes, say 48, is balanced out or compensated or bucked out by equal and opposed amplitude modulation in the other tube, say 42.

Modulation is accomplished by applying modulating potentials from any source, such as, for example, a microphone or a scanner through choking inductances RFC to the grid electrodes 54 and 56 in phase opposition. Increasing the potential on the grid 54 increases the current through the tube 48. Increasing the current through the tube 48 decreases the capacitive reactance provided by the said tube. This is equivalent to adding capacity to the tank circuit. Since the modulation is in phase opposition at this time, the current through the other tube, say 42, is decreased thereby increasing the inductive reactance provided by tube 42. This has the effect of adding inductance to the tank circuit. The added capacity and increased inductance shunt the tank winding 28 and alters the tune thereof slightly. Both the added shunt capacity and the higher shunt inductance decrease the resonant frequency of the circuit. Increasing the potential of grid 56 and decreasing the potential on the grid 54 has the opposite effect. Thus, the tubes are controlled to vary the reactance of the tank circuit in accordance with the modulating potentials. This modulates the phase of the oscillatory energy in the tank circuit and the phase modulated oscillatory energy may be utilized directly from the tank circuit through inductance 38 coupled therewith or may be used after amplification and multiplication to

the extent required in frequency multipliers and amplifiers in a unit 34.

The other phase modulator comprising the tube 33 on the lower part of the drawings is exactly identical to the one described above and the said description will not be repeated.

The operation of the phase modulator shown on the lower part of the figure is similar except for this important distinction. The operation here is in a sense opposite to the operation in the phase modulator in the upper part of the drawings. To insure this opposed phase modulation of the carrier, the leads between the modulation potential transformer 51 secondary are reversed; that is, the lead connected with the grid 56 of tube 42 of the described phase modulator is herein connected with the grid 54 of tube 48, while the end of the said secondary winding coupled to the grid 54 of tube 48 of the upper modulator is in the low modulator coupled to the grid 56 of the tube 42.

The phase modulated carrier from one of the balanced phase modulators is supplied by lead 38 to a multiplier 32 wherein it is multiplied, say N times. The phase modulated carrier from the other modulator, say the lower balanced modulator, is supplied by a lead 34 to a multiplier 36 wherein it is multiplied (N-1) times.

As described in connection with Figure 1, the multiplied phase modulated carriers are mixed in a converter 38 and supplied to additional multipliers and amplifiers.

My improved method and means has the advantage of reducing distortion due to non-linearity as the phase is not shifted the same amount on each side of zero phase shift for the same change reactance of the reactance tubes.

It has the additional advantage of reduction in concomitant amplitude modulation due to the action of the individual balanced phase modulators. These advantages considered together result in a substantially pure phase modulated wave, the wave deviation of which follows quite linearly the modulations to be transmitted.

I claim:

1. In a wave length modulation system, a source of oscillations of substantially constant frequency, two circuits each tuned to the frequency of said source and excited by oscillations generated by said source, a wave length modulator coupled to each tuned circuit, each wave length modulator comprising two electron discharge tubes each having electron receiving electrodes coupled to said tuned circuit and having control grids coupled to said tuned circuit, the said couplings being arranged to apply phase displaced voltages of the generated frequency on the electron receiving electrode and control grid of each tube, a coupling between the cathode of each tube of each modulator and the respective tuned circuit for effectively coupling the internal impedance of the tubes of each modulator in shunt to reactance of the respective tuned circuit, a source of modulating potentials, connections coupling said source of modulating potentials differentially to the tubes in one of said modulators, connections coupling said source of modulating potentials differentially to the tubes in the other of said modulators, said last named connections being relatively reversed with respect to said other connections between said source of modulation potentials and said tubes, a frequency multiplier coupled to each of said tuned circuits and a converter coupled to the frequency multipliers.

2. In a phase modulation system, a crystal

controlled oscillation generator arranged to generate oscillations of carrier wave frequency to be phase modulated in accordance with signals, two circuits each parallel tuned to the frequency of said generator coupled to said generator and excited by oscillations generated by said crystal controlled oscillation generator, a phase modulator coupled to each tuned circuit, each phase modulator comprising two electron discharge tubes each having electron receiving electrodes coupled to said tuned circuit and having control grids coupled to said tuned circuit, the said couplings being arranged to apply phase displaced voltages of the generated frequency on the electron receiving electrode and control grid of each tube, a coupling between the cathode of each tube of each modulator and the respective tuned circuit for effectively coupling the internal impedance of the tubes of each modulator in shunt to reactance of the respective tuned circuit, a source of modulating potentials, connections coupling said source of modulating potentials differentially to the tubes in one of said modu-

lators, connections coupling said source of modulating potentials differentially to the tubes in the other of said modulators, said last named connections being relatively reversed with respect to said other connections between said source of modulating potentials and said tubes, a converter, a first frequency multiplier coupling one of said tuned circuits to said converter and a second frequency multiplier the multiplication factor of which differs from the multiplication factor of the first frequency multiplier coupling the other of said tuned circuits to said converter.

5 15 20 3. A system as recited in claim 1 wherein one of said frequency multipliers has a multiplication factor which differs from the multiplication factor of the other of said frequency multipliers.

4. A system as recited in claim 2 including an electron discharge tube amplifier in each of the couplings between the tuned circuits and the crystal controlled generator.
